UNITED STATES PATENT OFFICE

WILLIAM A. CLARK, OF OAKLAND, CALIFORNIA

HELICOPTER

Application filed October 5, 1927. Serial No. 224,152.

This invention relates to a helicopter and particularly pertains to improvements in devices of this character as shown in Patent No. 1,516,001 issued to me November 18, 1924.

It is the principal object of the present invention to provide refinements in design of the helicopter, whereby it may travel through the air in a horizontal direction with added ease over any like structures now known and 10 and it is provided with lifting and propulsion means adapted to insure that it will be more effectively lifted and that a heavier weight may be lifted with the expenditure of less energy than is now required for a like 15 operation in devices now known. The present invention contemplates the provision of a frame structure carrying a power plant and mounted upon a running gear, the upper portion of said frame structure being fitted with 20 propulsion propellers and lifting propellers, the latter being so housed as to minimize the wind resistance and to increase the lifting power of the propellers.

The invention is illustrated by way of example in the accompanying drawings, in which—

Fig. 1 is a view in side elevation showing the device with which the present invention is concerned.

Fig. 2 is a view in end elevation showing the helicopter.

Fig. 3 is a view in plan showing the arrangement of the lifting propellers and the stream-line enclosure therefor.

Fig. 4 is an enlarged view in plan showing the details of the lifting propellers.

Fig. 5 is an enlarged view in central vertical section through the lifting propellers as seen on the line 5—5 of Fig. 4.

Referring more particularly to the drawings, 10 indicates a rectangular platform structure fitted with a running gear comprising front and rear axles 11 and 12 and wheels 13. Four wheels are here shown as being 45 provided so that the structure may be supported in an upright position. Mounted on the platform 10 is a power plant, here shown as including an internal combustion engine 14, which engine is provided with a driving 50 shaft 15 carrying friction pulleys 16 and 17.

These pulleys are spaced from each other and are adapted to alternately contact with clutch disks 18 and 19 slidably mounted upon a vertical shaft 20 disposed at right angles to the driving shaft 15. A lever 21 is provided 55 and operates forks 22 and 23 which engage collars upon the clutch disk and simultaneously shifts said collars and the disks associated therewith.

A superstructure is disposed above the platform 10 and comprises uprights 24 carrying an overhead rectangular frame structure 25. This frame structure consists of horizontal frame members 26 and 27 and vertical connecting members 28. The rectangular frame structure 25 supports lifting propellers 29 and 30 and their cylindrical housings 31 and 32. The rectangular frame structure extends beyond the housings 31 and 32 at its opposite ends and carries a frame structure 33 which comes to a point in front of the propeller housing 32 and extends rearwardly and outwardly to the sides of the member 32 and then along the sides as indicated at 34 to thereafter be brought around the cylindrical housing 31 and brought to a point of conversion in the rear of said housing, whereby a stream line effect will be produced to lessen the wind resistance which would otherwise be offered by the cylindrical housing members 31 and 32. The propellers 29 and 30 are fitted with vertical drive shafts 35 and 36, which shafts extend downwardly through suitable bearings and carry gears 37 and 38 respectively. These gears mesh with driving gears 39 and 40 and are driven by the shaft 20 through gears 41 and 42 mounted upon the shaft 20 and a shaft 43 respectively.

Due to the arrangement as shown in Fig. 1, it will be evident that the lifting propellers 29 and 30 will be constantly driven in opposite directions and it will be further understood that by manipulating the clutch disks 18 and 19, the direction of rotation of shaft 43 may be changed. The lifting propeller structure is intended to act to lift the helicopter from the ground or to be used in supporting the helicopter to permit it to land without violence.

A propeller structure 44 is disposed at the 100

forward end of the helicopter for the purpose of propelling the aircraft horizontally. This propeller is provided with a universal drive connection 45 which connects it with a horizontal drive shaft 46. The horizontal shaft is fitted with pulleys 47 and 48 upon which a belt 49 may be selectively disposed by a shifting rod 50. The pulley 47 is idle upon the shaft 46 while the pulley 48 is keyed thereto. It will thus be evident that when it is desired not to drive the horizontal propulsion propeller, the shifting of the belt 49 from the keyed shaft 48 to the shaft 47 will cause the propeller 44 to remain idle. An operating lever 51 is keyed to the shifting rod to facilitate in shifting the belt. The belt 49 passes around a suitable pulley 52 carried on the forward end of shaft 15 of engine 14. The propeller 44 may be disposed 20 in various positions in angular relation to its driving shaft 46 by manipulation of a spider 53. This spider has four arms disposed at right angles to each other and in the same plane, and the spider is mounted for 25 universal movement upon a bearing 54. Each of the arms is fitted with a cable 55 secured to the outer ends of arms 56 of a spider disposed adjacent the propeller 44 and carried upon a short propeller shaft 57 through which the propeller is driven from the universal joint 45. It is to be understood 30 that the frame structure comprising the platform 10 and the upper frame 25 may be suitably provided with transverse bracing to give 35 it rigidity and to insure that it will resist wind stresses. This bracing may be in the form of cables 58.

One of the principal features of improvement of the present device is the lifting propeller construction and it is to be understood 40 that, while the propellers 29 and 30 are here shown as disposed upon vertical axes for the lifting of the vehicle, it may be desirable to substitute a propeller of similar design for 45 the propeller 44 without departing from the spirit of the present invention. The propellers 29 and 30 are identical with the exception that their blades are pitched in opposite directions and that the two propellers move 50 in opposite directions, as indicated by the arrows A and B in Fig. 3.

The blades of the lifting propellers are also clearly shown in Fig. 4, where it will be seen 55 that the blades on propeller 29 are disposed at 45° to the blades on propeller 30. This has been proven to be of advantage in causing the two lifting propellers to balance each other and more satisfactorily cooperate in manipulation of the aircraft. The wings are warped 60 around the shaft for a distance slightly greater than 90° so that the upper and lower contiguous edges of adjacent blades will overlap as shown in Figs. 4 and 5. The marginal edge of each of the blades deflects downwardly to form a banking wing 63 against

which the air set in motion by the main warped portion of the blade will be thrown by centrifugal force and will be then deflected downwardly, the force of which action will increase the lifting efficiency of the blade. 70 In fact, experience has proven that by providing a propeller having straight warped blades 62 and a propeller having the blades with the outer deflecting margins 63, the last named structures will lift approximately 75 seven times the weight lifted by the straight warped blades when the two are driven at the same rate of speed and are of substantially the same over-all dimensions. The blades 62 thus formed are braced by guy 80 wires 64 which are secured to the shafts therefor at points above and below the propeller structures.

In the operation of the present invention, 85 the engine 14 is started and its shaft 15 is driven. It will be assumed that the shaft is rotating in a clockwise direction as viewed from the rear and that the friction wheels 16 and 17 will tend to rotate the disk 18 to cause the lifting propellers 29 and 30 to rotate in the direction of the arrows A and B as indicated in Fig. 3 of the drawings. This action will lift the aircraft and as the lifting propellers rotate, their blades will pass through the air to displace the air and will at the same time force the air out by centrifugal action against the deflecting margins 63 of the blade, thereby causing increased lifting action as the air is displaced and the aircraft is 90 lifted. When the aircraft has reached a desired elevation, the lever 59 may be operated to shift the belt 49 from the idler 47 to the pulley 48. This will establish a driving connection from the engine to the propeller shaft 46 and will drive the propulsion propeller 44. It will, of course, be understood that in the event ascension is to be made in an oblique direction to the ground, the propeller 44 may be driven before the elevation is 100 reached and, in fact, by manipulation of the spider 53, the propeller may be disposed at an angle to the horizontal so that it will assist in elevating the aircraft as it travels along its oblique course. If it is desired to reverse the 105 direction of rotation of the lifting propellers 29 and 30, the lever 21 may be operated to swing the disk 19 into engagement with the friction wheels 16 and 17 and to simultaneously move the disk 18 out of engagement therewith, thus reversing the direction of 110 rotation of the shaft 20.

It will thus be seen that the structure here disclosed provides improved means for the 115 operation of a heavier-than-air craft and that by the propeller construction here disclosed, improved lifting conditions may be brought about. It is also to be understood that while the propellers are shown as being used for lifting propellers, it may be desir- 120 125 130

able to use them for propulsion propellers, either in air or liquids.

I want to call particular attention to the fact that the blades of the lifting propellers extend radially about the propeller shaft and lie in substantially the same plane with their radial axis at right angles to the axis about which the propeller revolves.

I also desire to point out that these convolute blades of the lifting propellers are bent at their outer ends so that their tips will lie at an angle to the axis of the blades so as to intercept the centrifugal blast of air created by the propellers when in operation.

In this manner I utilize this centrifugal force to aid the propeller in lifting or pulling.

It is thus obvious that my propeller will be a great deal more efficient than those now in use because these latter entirely lose the effectiveness of the air escaping in a radial direction.

While I have shown the preferred form of my invention, it is to be understood that various changes may be made in its construction by those skilled in the art without departing from the spirit of the invention, as defined in the appended claims.

Having thus described my invention, what I claim and desire to secure by Letters Patent is:

1. A lifting propeller for a helicopter comprising four blades extending radially about the axis of the propeller and with their contiguous edges overlapping, the radial axis of said blades extending at right angles to the axis of the propeller, and the outer portions of said blades being inturned at an obtuse angle to the axis of the blades to intercept the centrifugal fluid blast created when the propeller is in operation.

2. A lifting propeller for helicopters comprising a plurality of blades extending radially about the axis of the propeller, the radial axis of said blades extending at right angles to the axis of the propeller, the outer portions of said blades being inturned at an obtuse angle to the axis of the blades and arcuate concentric to the axis of the propeller whereby said outer portions of the blades will intercept the centrifugal fluid blast and utilize the same in a lifting action.

3. A lifting propeller for helicopters comprising a plurality of helical blades extending radially about the axis of a propeller in circumferential alignment, the radial axis of said blades extending at right angles to the axis of the propeller, the outer portions of said blades being inturned at an obtuse angle to the radial axis of the blades and arcuate concentric to the axis of the propeller whereby said outer portions of the blades will intercept the centrifugal fluid blast and utilize the same in a lifting action.

WILLIAM A. CLARK.
